UNITED STATES PATENT OFFICE.

HARRY FULENWIDER AND JESSE FULENWIDER, OF SAVANNAH, GEORGIA.

HOLDING DEVICE FOR SHINGLES.

Application filed June 5, 1924. Serial No. 718,036.

This invention relates to holding devices for shingles and proposes the construction of means adapted to be fixedly secured, for supporting and holding flat the butt end of a shingle laid diamond-wise, and at the same time housing but not penetrating the adjacent corners of the underlying shingles of the previously laid course.

One of the objects of the invention is to provide means for performing the above-stated functions, so formed as to be definitely allocated by the adjacent corners of the shingles of the said underlying course, and having the shingle holding portions arranged to act as guides for the butt of the superposed shingle, so that the latter will automatically be positioned symmetrically when in place in the shingle holding device, without the necessity for an accurate determination of its position when laying the shingles.

Another object of the invention is to construct and arrange the exposed portions of the holding device so that they shall be of low visibility when in position on a roof, and of such nature as to accelerate the drainage of moisture therefrom.

Other objects of the invention relate to simplicity of manufacture and ease and convenience in use of the device.

Still other objects of the invention will appear as the description of the same develops.

In the drawings:—

Figure 1 is a plan view of a portion of a roof embodying a number of our improved holding devices for shingles.

Figure 2 is a plan view of a holding device for shingles on an enlarged scale.

Figure 3 is a section taken along the line 3—3 of Figure 2.

Figure 4 is an end view of Figure 2 viewed from above.

Referring now in detail to the several figures, the reference character *a* represents the lower or underlying row of any two successive courses of shingles with which our invention is associated. The reference character *b* denotes the second or superposed course of shingles. Our invention is designed to fit over the adjacent corners of adjoining shingles in the underlying course and to support by its butt a shingle of the overlying course.

The invention consists of a plate 1 preferably made of sheet metal and of any suit-

able dimensions which is preferably stamped so as to provide on opposite sides the embossed portions 2 and 3, said portions being of such form as to constitute right-triangular depressions on its lower surface. Said depressions are of a depth equal to the thickness of the shingles and fit over the corners of adjacent shingles in the course *a*, by which means the plate 1 is definitely allocated with respect to said course of shingles.

The plate 1 is provided adjacent its lower end with turned-up portions 4 and 5 forming ledges upon which the sides of the butt of a superposed shingle *b* are adapted to rest. The lower part of the plate 1 is preferably made wider than the upper part so as to permit the turned-up portions to be of relatively great length enabling them to serve as guides for automatically locating the superposed shingle in its proper position. These two features, that is to say, the depressions formed by the embossed portions 2 and 3 by which the holding device is located, and the turned-up portions 4 and 5 by means of which the shingle is positioned, permit the shingles of a course to be laid accurately and symmetrically without the necessity, on the part of the person who lays the shingles, of making an accurate determination of the position of the same.

The edges of shingles are usually cut in planes perpendicular to the surfaces thereof, and it is preferred to make the turned-up portions 4 and 5 with a curved base, or with a base which does not closely fit the sides of the shingles at the edges, thereby providing capillary space between the shingle and shingle holding device for the draining away of moisture from between the shingle and shingle holding device by capillarity. It may be advantageous, on account of the studied lack of close fit between the shingle and shingle holding device to provide the turned-up portions with fastening means such as the pointed lugs 6 and 7, adapted to penetrate the superposed shingle adjacent the edges thereof when the turned-up portions are struck with a hammer. It is, however, well within the scope of the invention to omit the pointed lugs and have the edges of the turned-up portions 4 and 5 engage the surface of the superposed shingle with frictional contact. The upper part of the plate 1 may be formed with holes 8

for nailing the holding device to the roof, or the holes may be omitted at the time of manufacture and the nails driven through the plate 1 at the time the shingle holding device is applied to the roof. It is to be understood that the nail holes are covered by the superposed shingle and that the nails do not penetrate the adjacent corners of the underlying course of shingles as in former devices, leaving the latter intact, yet held firmly in position by being housed beneath the embossed portions 2 and 3.

It is obvious that the form and configuration of our improved holding device for shingles can be modified to a certain extent without vitiating the effectiveness of a patent granted upon the invention, wherefore it is to be understood that the scope of the invention is not limited except by the express terms of the appended claims.

Having described our invention what we claim as new and desire to secure by Letters Patent, is:—

1. A device for holding shingles comprising a plate having depressions on its lower face fitting the adjacent corners of adjoining shingles in an underlying course, the lower part of said plate being formed with

ledges embracing the edges of the butt of a superposed shingle, said ledges being slightly wider at their base than the thickness of said superposed shingle. 30

2. A device for holding shingles comprising a plate having depressions on its lower face fitting the adjacent corners of adjoining shingles in an underlying course, the lower part of said plate being formed with ledges embracing the edges of the butt of a superposed shingle and being provided with shingle penetrable lugs, said ledges being slightly wider at their base than the thickness of said superposed shingle. 35

3. A device for holding shingles comprising a plate having depressions on its lower face fitting adjacent corners of adjacent shingles in an underlying course, the lower part of said plate being formed with ledges embracing the edges of the butt of a superposed shingle and being provided with shingle-engaging lugs, said ledges being slightly wider at their base than the thickness of said superposed shingle. 40 45

In testimony whereof we have hereunto set our hands.

HARRY FULENWIDER.
JESSE FULENWIDER.
